Primary Examiner — Garth Rademaker*Assistant Examiner* — Benjamin M Weeks(74) *Attorney, Agent, or Firm* — Sughrue Mion, PLLC(57) **CLAIM**

The ornamental design for binoculars, as shown and described.

DESCRIPTION

FIG. 1 is a perspective view of the binoculars, viewed from above and to the left of a front side thereof;

FIG. 2 is a perspective view of the binoculars, viewed from above and to the right of the front side;

FIG. 3 is a front view thereof;

FIG. 4 is a rear view thereof;

FIG. 5 is a top view thereof;

FIG. 6 is a bottom view thereof;

FIG. 7 is a right side view thereof; and,

FIG. 8 is a left side view thereof.

The broken lines show portions of the binoculars that are not being claimed, and thus form no part of the claimed design.

1 Claim, 8 Drawing Sheets(56)
